UNITED STATES PATENT OFFICE.

SAMUEL WEISSMAN AND RALPH WEISSMAN, OF DETROIT, MICHIGAN.

BED-SPRING.

1,340,510.

Specification of Letters Patent.

Patented May 18, 1920.

Application filed February 10, 1919. Serial No. 275,986.

To all whom it may concern:

Be it known that we, SAMUEL WEISSMAN and RALPH WEISSMAN, citizens of the United States of America, residing at Detroit, in the county of Wayne and State of Michigan, have invented certain new and useful Improvements in Bed-Springs, of which the following is a specification, reference being had therein to the accompanying drawings.

10 Our invention aims to provide a novel mattress spring embodying longitudinal resilient members connected by flexible transverse members, in contradistinction to coiled springs and resilient devices, the flexible members being more easy to install, less expensive, and possessing a degree of flexibility which does not impair the cushioning qualities of the mattress spring.

Our invention aims to utilize tubular or 20 hollow spirally wound or woven cables as transverse connecting members for the resilient body of a mattress spring, cushion, seat or the like, and provision is made for expeditiously connecting the cables to the 25 numerous resilient members of the mattress spring.

Our invention will be hereinafter specifically described and then claimed, and reference will now be had to the drawing 30 wherein—

Figure 1 is a plan elevation of a mattress spring, partly broken away, showing the improvement in connection therewith;

Fig. 2 is a similar view of another type of 35 spring, provided with the improvement;

Fig. 3 is a perspective view of a portion of the spring shown in Fig. 1;

Fig. 4 is a perspective view of a portion of the spring shown in Fig. 2, and.

40 Fig. 5 is a plan of a plurality of spiral springs connected by cables in accordance with our invention.

In Figs. 1 and 2 we have shown a spring frame composed of side rails 1 having the 45 ends thereof connected by heads 2, said spring frame being of a conventional form. In Fig. 1 the heads 2 of the frame are connected by a plurality of longitudinal parallel members 3, said members being in the 50 form of flat resilient strips having the ends thereof apertured and connected to the heads 2 by coiled retractile springs 4. The members 3 being comparatively flat afford a substantial body for the spring and to main-

tain said longitudinal members in parallel 55 relation, prevent undue sagging of one member relative to others, and afford a better body for the spring are spaced parallel transverse members 5 in the form of tubular or hollow spirally wound or woven flexible cables which have the ends thereof connected to the outermost longitudinal member 3.

All of the longitudinal members 3 are provided with parallel slits 6 and the material between the slits is depressed to provide straps 7, said straps coöperating with the marginal edges of the longitudinal members 3 in forming transverse eyes to receive the transverse flexible cable 5, thus allowing 70 the greater part of each longitudinal member, at the eyes, to bear upon the transverse members and provide a connection such as shown in Fig. 3.

In Fig. 2 of the drawing, the longitudinal 75 members are each made of wire oblong links 8 having loop and hook connected ends, and in this instance the transverse members 10 extend through the hook ends 9 of the links 8 and coöperate in supporting the longitudinal members, the outermost of which are similar to the longitudinal members shown in Fig. 1.

It is also possible to use tubular or hollow cables for connecting the confronting 85 or adjacent convolutions of spiral springs 12 entering into the construction of mattress springs, cushion or somewhat similar structures, said cables having a degree of flexibility that contributes to the yieldability 90 of the spring body, and from a manufacturing standpoint materially reducing the cost of a spring by permitting of the same being expeditiously and economically made.

While in the drawings there are illustrated the preferred embodiments of our invention, it is to be understood that the structural elements are susceptible to such changes, in size, shape and manner of assemblage, as fall within the scope of the appended claim.

What we claim is:—

In a mattress spring, the combination of a frame, longitudinal flat members connecting the ends of said frame and having the upper 105 faces thereof devoid of protuberances and disposed in a common plane, said members having parallel slits therein with the mate-

rial between said slits depressed to provide eyes at the lower faces of said members, and cables having the ends thereof connected to the outermost longitudinal members and extending through the eyes of said members so that said members may rest on said cables and relieve the slotted material of strains incident to a body on the spring.

In testimony whereof we affix our signatures in presence of two witnesses.

SAMUEL WEISSMAN.
RALPH WEISMAN.
